UNITED STATES PATENT OFFICE.

WILLIAM J. PRICE, OF POTEAU, OKLAHOMA.

STOCK-GUARD.

1,241,763.

Specification of Letters Patent.

Patented Oct. 2, 1917.

Application filed November 16, 1916. Serial No. 131,795.

To all whom it may concern:

Be it known that I, WILLIAM J. PRICE, a citizen of the United States of America, residing at Poteau, in the county of Le Flore 5 and State of Oklahoma, have invented a new and useful Improved Stock-Guard, of which the following is a specification.

This invention relates to new and useful improvements in stock guards for railways, 10 and the primary object of the invention is to provide a simple and efficient type of stock guard which includes a plurality of hingedly mounted slats normally inoperative, but operable by means of the depression 15 of a step plate to prevent stock from entering upon the right-of-way, but will enable the stock to pass off the right-of-way to the outside without molestation.

A further object of the invention is to provide a simple and efficient type of stock guard of this character which may be operated without a pit, and without materially disturbing the road bed. The device owing 20 to its extreme simplicity may be applied 25 without the assistance of an expert, said application being so simple that it may be easily attached by the section crew.

A still further object of the invention is to provide a simple and efficient stock guard 30 of this character which is operable by a step plate, that is connected with hingedly mounted guard slats, said step plate having a counter-balancing means associated therewith in the connection, whereby the minimum weight necessary to depress the plate 35 may be varied. This adjustment enables the device to be used for heavy animals only or for light and heavy animals to operate the same.

40 A further object of this invention is to provide a stock guard of this character with means that will protect the same from being torn up by anything dragging attached to a car or train, and also which protects 45 the guard from damage by beams or timbers falling thereon.

A still further object of this invention is to provide a device of this character which is easily and simply constructed, inexpensive to manufacture, and one which will be 50 very efficient in operation.

With these and numerous other objects in view, my invention consists of the novel features of construction, combination and arrangement of parts which will be herein re-

ferred to and more particularly pointed out in the specification and claims.

In the accompanying drawings.

Figure 1 is a top plan view of the stock guard;

Fig. 2 is a transverse section taken on the line 2—2 of Fig. 1; and

Fig. 3 is a detail end view of a portion of the guard operating means.

In describing my invention, I shall refer 65 to the drawings in which similar reference characters designate corresponding parts throughout the several views. The exterior features of my new and improved stock guard are best illustrated in Fig. 1 of the 70 drawings, and the same includes a transversely extending step plate or treadle *a*, that is mounted beneath the rails of the railway track, one side edge of said plate being 75 hingedly mounted as shown at *a* to one of the ties. The hinges are positioned at the side of said ties, adjacent the upper edges thereof, so that in normal position the plate *a* will be disposed horizontally, in alinement, or substantially a single plane with the top portions of the railway ties that support the 80 rails.

The primary barrier that stops the stock, is formed of a plurality of longitudinally extending slats *c* which are hingedly mounted 85 at *e* on the tops of adjacent railway ties, said slats extending parallel with the rails, and positioned between said rails, centrally with respect to the same is a rigid guard strip *b*, which is not hingedly mounted, and 90 is normally positioned upright, to protect the slats *c* from falling timbers or the like. All of the slats *c* are provided with beveled ends, as is the rigid center strip *b* for a purpose to be hereinafter more fully described. 95

Adjacent the ends of the slats *c* are transversely extending guard strips *d*, having inclined upper faces, with their upper edge disposed adjacent the lower edge of the inclined ends of said slats. These strips *d* are 100 positioned one on the inner edge of the step plate *a* adjacent the hinges thereof, and the other on the outer tie that supports the opposite ends of the slats. These upwardly inclined guard strips are adapted to lift timbers or the like that are dragged by a passing car or train over the guard, and hence prevent damage to the same.

The operating means employed in this device includes a pair of rock shafts, that are 110

rotatably mounted beneath the slats *c* and step plate *a* respectively. The rock shaft that is mounted beneath the slats *c* is designated by the letter *K* and is rotatably mounted in depending bearings *f* that are supported from a tie, disposed between the ties that support the slats *c*. This rock shaft *K* extends transversely beneath the longitudinally extending slats, and has mounted therein a downwardly extending arm *j* that is preferably disposed centrally with respect to the shaft. The shaft *K* is also provided with a plurality of lateral, horizontally extending arms *h*, that extend inwardly toward the step plate *a* a short distance, and which have connected with their outer ends shown at *s*, upwardly extending link members *i*. A plurality of these connections are formed on the rock shaft, one being disposed beneath each of the slats *c*, and the slats *c* are provided on their under side adjacent the free edges with projecting studs, that are adapted to be connected with the link members *i* as shown at *g*. By this connection, owing to the fact that the slats *c* are normally disposed in alinement, that is lying flush with the top portions of the railway ties, upon movement of the shaft *K*, the slats *c* will be raised to form a barrier, to prevent the stock from moving thereover.

The rock shaft that is disposed beneath the step plate *a*, and which is designated by the letter *q* is rotatably mounted in laterally extending bearings that project from one side of the railway tie disposed adjacent the free end of the plate *a*. This shaft *q* has an upwardly projecting arm *o* extending therefrom, said arm *o* being preferably disposed centrally with respect to the same, and the said arm is connected with the arm *j* of the shaft *K* by a link member *l*, said link *l* having its inner end connected as shown at *S* with the free end of the arm *o*. This connection between the shafts *q* and *K* will be adapted to rock said shafts simultaneously.

The step plate *a* has secured to the outer free end thereof adjacent its edge, a depending portion *p* that has its free end or extremity disposed substantially in alinement with the shaft *q*. The said portion *p* is connected with the shaft *q*, by horizontally extending arm *n*, that extends through said shaft, and has its free end projecting therefrom. Slidably mounted on the free end of the shaft *n* is a counter-balancing weight *m*, for a purpose to be hereinafter more fully described.

In operation, when the stock guard is placed on a railway track, the step plate *a* is disposed adjacent the road or lane, which the device is best adapted to be operatively associated with, and it is obvious that should the stock attempt to pass from the roadway onto the right-of-way, they will step upon the plate *a* and hence raise the slats *c* to

form a barrier, which will prevent further passage. As soon as the stock moves from the plate *a*, the various parts of the device will return to normal position. As the slats *c* are normally lying flat, stock will be able to pass from the right-of-way onto the roadway without molestation.

When the stock steps upon the plate *a*, the same is depressed, and the connection of said plate with the rock shaft *q* will hence rock said shaft, whereupon owing to the fact that the shaft *q* is operatively connected with the shaft *K* said shaft will be correspondingly rocked, and as the shaft *K* is connected with each of the slats, the arms *h* will be moved upwardly to raise said slats owing to the connection of said arms, with each of the slats. As soon as the stock moves back from the plate *a*, it is obvious that the various parts of the device will return to normal position, and the slats will once more resume their normal flat position on the top of the ties.

The adjustable weight *m* on the free end of the arm *n*, permits the minimum weight necessary to depress the plate *a* to be varied. This permits the stock guards to be adjusted, so that when desired the device will only operate when cattle step upon the plate *a* or upon movement of the counter-balancing weight *m* the device may be operated by smaller animals as well as the larger ones. The rigid upwardly projecting center strips *b*, and the coacting inclined guard strips *d* at the opposite ends of the slats *c*, prevent any injury of the device from falling timbers or dragging articles carried by passing cars or trains.

From the above description taken in connection with the accompanying drawings, it is thought that a clear and comprehensive understanding of the construction, operation and advantages of my invention may be had, and while I have shown and described the device as embodying a specific structure, I desire that it be understood that such changes may be made in said structure as do not depart from the spirit and scope of the invention as claimed.

Having fully described my invention, what I claim as new, and desire to secure by Letters Patent, is:

1. In a cattle guard for railway tracks the combination of a transversely arranged movable step plate, a plurality of longitudinally extending hingedly mounted guard slats normally lying flat, a connection between said slats and the plate adapted to raise said slats upon depression of the plate, and adjustable counter-balancing means in said connection whereby the minimum weight necessary to depress the plate may be varied.

2. In a cattle guard for railway tracks the combination of a transversely arranged movable step plate, a plurality of longitudinally

- extending hingedly mounted guard slats normally lying flat, a pair of rock shafts mounted beneath said plate and slats respectively, a connecting link between said slats to move the same simultaneously, one shaft being operably connected with the plate, and a separate connection between each slat and the other shaft. 5
3. In a cattle guard for railway tracks the combination of a transversely arranged movable step plate, a plurality of longitudinally extending hingedly mounted guard slats normally lying flat, a pair of rock shafts mounted beneath said plate and slats respectively, upwardly and downwardly extending arms on the respective shafts, a link connecting said arms, a depending projection on the plate, a supplemental arm on the shaft beneath said plate connected with said projection, and means for connecting the other shaft and the slats to raise said slats upon movement of the shaft. 10
4. In a cattle guard for railway tracks the combination of a transversely arranged movable step plate, a plurality of longitudinally extending hingedly mounted guard slats normally lying flat, a pair of rock shafts mounted beneath said plate and slats respectively, upwardly and downwardly extending arms on said respective shafts, a link connecting said arms, a depending projection on the step plate, a supplemental arm extending transversely through the shaft beneath the step plate, said arm having one end connected with the depending projec- 15
- tion, a counter-balancing weight adjustably mounted on the operatively projecting end of said arm, and means for connecting the other shaft and the slats to raise said slats upon movement of the said shaft. 20
5. In a cattle guard for railway tracks the combination of a transversely arranged movable step plate, a plurality of longitudinally extending hingedly mounted guard slats normally lying flat, a pair of rock shafts 45 mounted beneath said plate and slats respectively, a connecting link between said shafts to move the same simultaneously, one shaft being operably connected with the plate, a plurality of laterally projecting arms on the other shaft, a projecting stud on the lower side of each slat, and a link connecting each stud with one of the laterally projecting arms on said last mentioned shaft. 50
6. In a cattle guard for railway tracks the combination of a transversely arranged movable step plate, a plurality of longitudinally extending hingedly mounted guard slats normally lying flat, said slats having beveled ends, a rigid center strip extending parallel 60 with the slats and having its opposite ends beveled correspondingly, inclined guard members adjacent the ends of said strip, and a connection between the plate and slats adapted to raise said slats upon depression 65 of the plate. 30
